UNITED STATES PATENT OFFICE.

WILLIAM F. ROTHENBERG, OF DENVER, COLORADO.

VENTILATING-FAN.

1,074,017.

Specification of Letters Patent. Patented Sept. 23, 1913.

Application filed April 24, 1912. Serial No. 892,928.

To all whom it may concern:

Be it known that I, WILLIAM F. ROTHENBERG, a citizen of the United States, residing at Denver, in the county of Denver and State 5 of Colorado, have invented certain new and useful Improvements in Ventilating-Fans; and I do hereby declare the following to be a full, clear, and exact description of the invention, such as will enable others skilled in 10 the art to which it appertains to make and use the same.

This invention relates to ventilating fans and has for an object to provide a fan especially adapted for operating in constricted 15 positions and to draw in air at the center and discharge it at or adjacent the circumference.

A further object of the invention is to provide a fan of the general type illustrated 20 in Patent No. 995,725 issued June 25th, 1911, but is an improvement thereon.

A further object of the invention is to provide a fan having blades so constructed as to permit the fan to be run in either 25 direction with equally efficient service.

A further object of the invention is to provide a fan having blades extending in a radial plane and with a closed back inclosing such blades and with a central disk covering 30 a portion of the central ends of the blades opposite the back.

With these and other objects in view the invention comprises certain novel constructions, combinations and arrangement of 35 parts as will be hereinafter more fully described and claimed.

In the drawings:—Figure 1 is a view of the improved fan in diametrical section associated with an intake air pipe. Fig. 2 is a 40 view of the fan in side elevation associated with an intake air pipe and with an outlet pipe surrounding such fan. Fig. 3 is a view of the fan in front elevation.

Like characters of reference indicate corresponding parts throughout the several views.

The improved fan which forms the subject matter of the present application comprises a dished back or casing 10 having a 50 spider 11 rigidly secured to its back and provided with a hub 12 adapted to accommodate a shaft 13 by which the spider and casing are rotated.

Within the casing 10 a plurality of blades

14 are erected, such blades being positioned 55 upon radial planes extending from a central tube 15 to the outer periphery of the casing 10 and preferably wider than the depth of the dished casing. At the center of the tube 15 and the blades 14 connected therewith a 60 disk 16 is provided covering the inner ends of the blades and serving to strengthen such blades, the blades preferably being inclined along their outer sides from such disk to the outer periphery of the dished casing. 65

While not essential to the present invention, it is desirable to operate the fan in conjunction with an intake pipe shown at 17, the diameter of said pipe being greater than the diameter of the disk 16 and having 70 its open end disposed adjacent such disk with an open annular space surrounding such disk. When the fan is rotated in either direction the centrifugal force of the blades 14 will cause the air to be thrown outwardly 75 as indicated by the arrows and unless confined such air will of course be circulated freely about the fan. Under certain conditions it is desirable to put an outlet pipe or casing 18 around said fan as shown in Fig. 80 2 whereby the air thrown from said fan is retained within the casing and discharged as indicated by the arrows in said Fig. 2.

I claim:

1. In a device of the class described comprising a pipe for admitting air, a fan axis placed in line with said pipe, a dished back secured to said axis, blades parallel with the axis of the pipe, a disk secured to said axis and adapted to obstruct part of the pipe, 80 said blades extending between said disk and dished back and means for rotating with the axis.

2. In a device of the class described comprising a pipe having an outlet, a fan axis 95 disposed before the outlet of said pipe, a dished back rigid with said axis, a disk rigid with said axis and parallel with the plane portion of the dished back, blades perpendicular to the disk and secured to the 100 axis and means for rotating the axis.

In testimony whereof I affix my signature in presence of two witnesses.

WILLIAM F. ROTHENBERG
